UNITED STATES PATENT OFFICE.

JOHN L. SCHEU, OF SUSANVILLE, CALIFORNIA.

CUFF-CLASP.

1,203,055.

Specification of Letters Patent. Patented Oct. 31, 1916.

Application filed May 28, 1915. Serial No. 30,883.

To all whom it may concern:

Be it known that I, JOHN L. SCHEU, a citizen of the United States, and a resident of Susanville, in the county of Lassen and State of California, have invented a new and useful Cuff-Clasp, of which the following is a specification.

The invention contemplates an improved clasp for holding the edges of a shirt sleeve 10 cuff properly together.

Referring to the drawings, Figure 1 is a view illustrating the clasp holding the edges of a shirt sleeve cuff together. Fig. 2 is a side view of the clasp alone. Fig. 3 is a sectional view of the clasp taken on line x^3-x^3 of Fig. 2. Fig. 4 is a sectional view of the clasp taken on the line x^4-x^4 of Fig. 2. Fig. 5 is an end view of one of the clasp members. Fig. 6 is a side view of one of the 20 clasp members. Fig. 7 is a side view of the other clasp member. Fig. 8 is a side view of the clasp, illustrating how the two members thereof are brought together to be fastened together. Fig. 9 is a sectional view 25 taken on line x^9-x^9 of Fig. 8. Fig. 10 is a sectional view taken on line $x^{10}-x^{10}$ of Fig. 2.

The clasp comprises two members 1 and 2. The member 1 is formed with a curved 30 flange 3 and a flat hollow female shank 4 which extends from said flange at right angles thereto. The side wall 5 of the said shank is secured to the flange 3 while the opposite side wall 6 of the shank is separated 35 from said flange, as indicated at 7, which gives said wall an inward and outward spring action, the separation extending around the edge walls 8 of the shank to the inner surface of the side wall 5, as shown in 40 Fig. 4, so as to give said wall a maximum spring action. The wall 6 is provided with a button hole 9. The member 2 is formed with a curved flange 10 and a flat male shank 11 which extends from the flange 10 45 at right angles thereto and is adapted to telescope with and fit snugly within the hollow shank 4. A button 12 is riveted to the shank 11, which extends slightly above the surface of one side of said shank and is 50 adapted to fit the button hole 9. The side edges 13 of the shank 10 are beveled inwardly toward the button side of the shank to permit the edge walls 8 of the hollow shank 4 to spring inwardly under the influence of the outward spring action of the 55 wall 6, when the shank 11 is introduced into

the hollow shank 4 and the wall 6 is engaged and sprung outwardly by the button 12, thus allowing the wall 6 to spring outwardly with its maximum spring action. The side 60 edges 8 of the hollow shank 4 diverge slightly outwardly from the flange 3, while the side edges 13 of the shank 11 converge slightly outwardly from the flange 10, so that the shank 11 may be readily introduced into the 65 hollow shank 4 and will fit snugly in said hollow shank when all the way therein, and prevent relative side movement of said members.

In placing the clasp in clasping position 70 in the cuff, the members 1 and 2 being separated and the edges of the cuff being brought together, the shank 4 of the member 1 is introduced from the outside of the cuff through the two button holes 15 in the edges 75 of the cuff so that the flange 3 engages the outside of one of the sides of the cuff. The shank 11 is then properly introduced into the end of the hollow shank 4 and the members 1 and 2 pressed toward each other, during 80 which operation the button 12 first engages and presses the wall 6 upwardly against its spring action so as to pass thereunder as shown in Figs. 8 and 9, and when the button has been brought into registration with the button hole 9, the wall 6 springs inwardly against the shank 10 and the button snaps into the button hole, and clasps the members 1 and 2 and the edges 85 of the cuff together as shown in Fig. 1. Any tendency of the edges of the cuff to spread apart will apply opposing forces to corresponding ends of the flanges 3 and 10, which will cause the shank 11 to bind against the 90 inside of the edge walls of the shank 4 and prevent the clasp members and the edges of the cuff from pulling apart.

The clasp members may be disengaged by placing one's fingers between the edges of the cuff and applying opposing forces to the flanges 3 and 10 in a line which extends diametrically through the button 12 and button hole 9 and which forms the axis of telescoping movement of the shanks 4 and 11. The curvature of the flanges 3 and 10 is such 100 that when the clasp is in the cuff, they engage the opposite sides of the cuff and bring said sides together with graceful curves. The width of the shank 4 is such that it fills the button holes 15 of the cuff longitudinally 105 and holds the ends of the cuff parallel and prevents the flanges 3 and 10 from pulling 110

out of the cuff button holes, and especially if the cuff is soft.

The upper edge of the button 12 may be rounded slightly so that the button may pass under the outer edge of the shank wall 6 and under the edge of the button hole 9.

In case the button 12 wears out it may be punched out of the flange and another button riveted to the shank in its place.

10. The two clasp members may be connected together as for example by a chain, which may extend over the side edges of the cuff when the clasp is in the cuff.

15. The edge walls 8 extend substantially at right angles to the side walls of the shank 4 so that said walls may be sprung inwardly over the beveled edges 13 of the shank 11 under the influence of the outward spring action of the wall 6.

20. I claim:

A clasp comprising in its entirety a pair of flat telescoping shanks, a flange connected

to each of said shanks, the female shank being rectangular in cross section and having side and edge walls, one of said side walls 25 and the edge walls being resilient, said last mentioned side wall being separated from the flange to which the shank is connected and formed with a button hole extending therethrough and a button on the shank to spring said resilient side wall outwardly and snap into the button hole, the side edges 30 of the male shank being beveled inwardly toward the button allowing the edge walls to spring inwardly to increase the spring 35 action of the resilient side wall.

In testimony whereof I have hereunto set my hand at San Francisco, California, this 14th day of May 1915.

JOHN L. SCHEU.
